HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

1,215,487.

Specification of Letters Patent. Patented Feb. 13, 1917.

Application filed September 2, 1916. Serial No. 118,243.

To all whom it may concern:

Be it known that I, HENRY P. CLAUSEN, a citizen of the United States, residing at Mount Vernon, in the county of Westchester and State of New York, have invented certain new and useful Improvements in Telephone Systems, of which the following is a full, clear, concise, and exact description.

This invention relates to telephone systems, and more particularly to those systems in which a plurality of telephones are connected to a single subscriber's line circuit.

The object of this invention is to provide improved signaling means for such telephone systems.

In accordance with one feature of this invention, a line circuit, to which a main and an extension telephone are connected, is provided with signaling means whereby a party at the main telephone, upon responding to the actuation of the usual signal and finding that the call is for the party at the extension telephone, can, by actuating a key, start the operation of a signaling device for the extension telephone. If, then, the party at the extension telephone does not answer within a predetermined period of time, the signaling device furnishes a characteristic indication of this fact whereupon the first party may again take control of the line by removing his receiver from its hook, or, by disregarding the signal, may allow the apparatus to be automatically restored to its normal position.

This invention will be more fully understood by reference to the drawing showing one embodiment of the invention, in which all the apparatus is shown in its normal and unactuated condition; wherein Figure 1 shows a subscriber's main telephone, an extension telephone and signaling apparatus connected to a subscriber's line circuit; and Fig. 2 shows in perspective a portion of the switching mechanism of the signaling apparatus.

In Fig. 1 of the drawing, A is a subscriber's main telephone, B an extension telephone, and C signaling apparatus associated with line wires 1 and 2 forming a line circuit. It is believed that this invention will be fully understood from a description of

the operation of the system shown in the drawing, and it will be so described.

It will be assumed that the operator at 55 the central office has completed a connection with the subscriber's line circuit, and that the ringer at main telephone A has been operated by ringing current from the central office. It will be further assumed that the 60 party at main telephone A, upon answering the call, finds that the party at the extension telephone B is desired. In order to signal the party at extension telephone B, the party at the main telephone A actuates a key 3 and 65 at the same time restores the receiver to the switchhook. The actuation of key 3 causes the energization of a stepping magnet 4 over a circuit from battery 5, through engaged contact springs 7, 7, winding of stepping 70 magnet 4 and the contacts of key 3 back to battery 5. Upon being energized, stepping magnet 4 attracts an armature 10 pivoted at 6, the upper end of which carries a spring-pressed stepping pawl 8, and the lower 75 end of which normally maintains contact springs 7, 7 in engagement. Upon the attraction of armature 10, the stepping pawl 8 engages a tooth of a ratchet wheel 11 to advance it one step in the direction indicated by the arrow, and permits the disengagement of contact springs 7, 7. The ratchet wheel 11 carries with it a wiper 12 and a cam 13. At the completion of the first step of ratchet wheel 11, the cam 13 engages the 80 free end of contact spring 32, moving it into engagement with contact spring 33, and wiper 12 permits the engagement of contact springs 14, 14 and 16, 16. The engagement of these contact springs causes 85 the energization of a holding magnet 18 over a circuit from battery at the central office (not shown) over line wire 2, winding of the holding magnet 18, engaged contact springs 32, 33, then in parallel through 90 contact springs 14, 14 and 16, 16 and the transmitters at main telephone A and extension telephone B, and then over line wire 1 back to the battery at the central office. Current in this path causes the operation of 100 the usual supervisory relay in the calling end of the cord circuit to efface the supervisory signal. Upon being energized the holding magnet 18 attracts an armature 21

pivoted at 19, the upper end of which carries a spring-pressed holding pawl 31, and the lower end of which controls the engagement of contact springs 23, 23. Upon the 5 attraction of armature 21, the holding pawl 31 engages a tooth of ratchet wheel 11 to prevent it from moving backward under the force exerted by a spring 22 connected to the wiper 12, while the armature 10, now 10 unattracted due to the deenergization of stepping magnet 4 following the disengagement of contact springs 7, 7, is being returned to its normal position by spring 20 preparatory to taking another step. The 15 engagement of contact springs 23, 23 establishes a shunt circuit around key 3, thereby rendering the circuit for the stepping magnet 4 independent of key 3. The stepping magnet 4 now alternately attracts and releases the armature 10 as it is energized at the beginning of each step by the engagement of contact springs 7, 7, and deenergized at the completion of each step by the disengagement of contact springs 7, 7. The 20 step-by-step rotation of ratchet wheel 11 causes the wiper 12 to move into successive engagement with contacts 24, thereby intermittently operating signaling devices 26 and 27 located respectively at stations B and A 25 over a circuit from battery 5, through wiper 12, one of the contacts 24, signaling devices 26 and 27 in parallel, back to battery 5. Assuming that the party at extension telephone B does not answer by removing his 30 receiver from the switchhook within the predetermined period of time needed for wiper 12 to pass over contacts 24, wiper 12 will move into successive engagement with contacts 25, thereby connecting battery 30 35 in series-aiding connection with battery 5, and causing an increase of current through the signaling devices 26 and 27. The increase of current through signaling devices 26 and 27 causes each of them to give a 40 characteristic signal different from that just previously given when battery 30 was not in the circuit. The signal given when batteries 5 and 30 are in series is, as before mentioned, different from that given when 45 battery 5 alone is in circuit, and this characteristic signal is for the purpose of advising the party at the main telephone A that the other party has not answered. If the main telephone A and the extension telephone B are so located that a single signaling device can be heard by the parties at 50 both telephones, then one of the signaling devices either 26 or 27 may be omitted. Further assuming that neither party responds to this characteristic signal, the 55 wiper 12 will move out of engagement with the last contact 25. The cam 13 thereupon moves out of engagement with the contact spring 32, allowing it to resume its normal 60 position and to disengage contact spring 33.

The disengagement of contact springs 32 and 33 causes the deenergization of the holding magnet 18, whereupon spring 9 returns armature 21 to its normal position, causing holding pawl 31 to move out of engagement 70 with the ratchet wheel 11, and permitting the disengagement of contact springs 23, 23. The disengagement of the contact springs 23, 23 opens the circuit of stepping magnet 4, which thereupon releases its armature 10. 75 The ratchet wheel 11 is thereupon returned to normal position, and contact springs 7, 7 are again in engagement. Upon the return of the ratchet wheel 11 to normal position, the hereinbefore traced circuit, including 80 the central office battery, is opened, whereupon the supervisory relay will release to cause the operation of the disconnect signal. In order that the holding magnet 18 may not be energized at any time during the 85 return of the ratchet wheel 11 to normal position, the rearward end of the cam 13 is bent upward so that during the return of the ratchet wheel 11 to normal position, the free end of contact spring 32 travels along 90 the under side of the cam 13. This is more clearly shown in Fig. 2.

Should the party at extension telephone B have answered while the signaling device 26 was in operation, the removal of the receiver from the switchhook would place a winding of induction coil 34 in shunt of the winding of the holding magnet 18. The resistance of this shunt path is low compared with the resistance of the winding of 100 holding magnet 18, so that the armature is now released and retracted to normal position, whereupon all the signaling apparatus is returned to normal position, and the operation of the signaling devices 26 and 27 is 105 stopped.

It will also be seen that should the party at the main telephone A have removed the receiver from the switchhook while the signaling devices 26 and 27 were in operation, 110 the holding magnet 18 would have released its armature 21 and all signaling apparatus would have been returned to normal position in the manner hereinbefore described.

It is thus seen that either the party at 115 main telephone A or the party at the extension telephone B can obtain control of the line at any time by removing their respective receivers from the switchhooks, and further, that should neither party answer 120 the call after the signaling mechanism has once been started, the mechanism will automatically release the line and return to its normal condition after a period of time determined by the adjustment of the apparatus. 125

In the systems of signaling previously used for this class of service, it has been necessary for the party answering the call to wait upon the line until the party at the ex- 130

tension telephone responded. This resulted in a considerable loss of time on the part of the answering party. Such a loss of time has clearly been obviated in a system in accordance with this invention, since it allows the party at the main telephone to at once restore his receiver to its hook, knowing that the improved signaling means will satisfactorily summon the party at the extension telephone, or failing to get a response, will so advise him in order that he may again converse with the calling party, or, not desiring to do this, he will know that the line will automatically be released and that all the apparatus will be restored to its normal condition.

What is claimed is:

1. In a telephone system, a line circuit, a plurality of subscribers' telephones connected thereto, a signaling device for one of the telephones, apparatus adapted when started to operate continuously for a predetermined period of time to cause the operation of the signaling device, and means controlled at another of the telephones for starting the apparatus.

2. In a telephone system, a line circuit, a main and an extension telephone connected thereto, a signaling device for the extension telephone, apparatus adapted when started to operate for a predetermined length of time, means controlled at the main telephone for starting the apparatus, and a source of current brought into circuit with the signaling device by the operation of the apparatus.

3. In a telephone system, a line circuit, a main and an extension telephone connected thereto, a signaling device for the extension telephone, an electromagnetically controlled step-by-step device adapted when started to operate for a predetermined length of time, means controlled at the main telephone for starting the step-by-step device, and a source of current brought into circuit with the signaling device by the operation of the step-by-step device.

4. In a telephone system, a line circuit, a main and an extension telephone connected thereto, a signaling device for the extension telephone, an electromagnetically controlled step-by-step device adapted when started to operate for a predetermined length of time, means controlled at the main telephone for starting the step-by-step device, a source of current brought into circuit with the signaling device by the operation of the step-by-step device for causing the signaling device to furnish a signal, and means brought into circuit with the source of current and the signaling device at a predetermined advanced position of the step-by-step device for causing the signaling device to furnish a different signal.

5. In a telephone system, a line circuit, a

main and an extension telephone connected thereto, a signaling device for the extension telephone, an electromagnetically controlled step-by-step device adapted when started to operate for a predetermined length of time, means controlled at the main telephone for starting the step-by-step device, a source of current brought into circuit with the signaling device by the operation of the step-by-step device for causing the signaling device to furnish a signal, and a second source of current brought into circuit with the signaling device at a predetermined advanced position of the step-by-step device for causing the signaling device to furnish a different signal.

6. In a telephone system, a line circuit, a main and an extension telephone connected thereto, a signaling device for the extension telephone, apparatus adapted when started to operate for a predetermined length of time for causing the operation of the signaling device, means controlled at the main telephone for starting the apparatus, and means controlled at one of the telephones for stopping the operation of the signaling device.

7. In a telephone system, a line circuit, a main and an extension telephone connected thereto, a signaling device for the extension telephone, an electromagnetically controlled step-by-step device adapted when started to operate for a predetermined length of time, means controlled at the main telephone for starting the device, a source of current brought into circuit with the signaling device, and means controlled at one of the stations for interrupting the circuit of the signaling device.

8. In a telephone system, a line circuit, a main and an extension telephone connected thereto, a signaling device for the extension telephone, an electromagnetically controlled rotatable device adapted when started to operate for a predetermined length of time, means controlled at the main telephone for starting the rotatable device, a source of current brought into circuit with the signaling device by the operation of the rotatable device for causing the signaling device to furnish a signal, and means brought into circuit with the source of current and the signaling device at a predetermined advanced position of the rotatable device for causing the signaling device to furnish a different signal.

9. In a telephone system, a line circuit, a main and an extension telephone connected thereto, a signaling device for the extension telephone, an electromagnetically controlled rotatable device adapted when started to operate for a predetermined length of time, means controlled at the main telephone for starting the rotatable device, a source of current brought into circuit with the signal-

ing device by the operation of the rotatable device for causing the signaling device to furnish a signal, and a second source of current brought into circuit with the signaling device at a predetermined advanced position of the step-by-step device for causing the

signaling device to furnish a different signal.

In witness whereof, I hereunto subscribe my name this 1st day of September, A. D. 1916.

HENRY P. CLAUSEN.
